[57] CLAIM

The ornamental design for a perfume bottle, as shown and described.

DESCRIPTION

FIG. 1 is a perspective view of the design for a perfume bottle according to the invention;

1 Claim, 6 Drawing Sheets

FIG. 2 is a side view of the design for a perfume bottle according to the invention;

FIG. 3 is a rear view of the design for a perfume bottle according to the invention;

FIG. 4 is a front view of the design for a perfume bottle according to the invention;

FIG. 5 is an overhead view of the design for a perfume bottle according to the invention;

FIG. 6 is an underside view of the design for a perfume bottle according to the invention;

FIG. 7 is a perspective view of a second embodiment of a perfume bottle according to the invention;

FIG. 8 is a side view of a second embodiment of a perfume bottle according to the invention;

FIG. 9 is a rear view of a second embodiment of a perfume bottle according to the invention;

FIG. 10 is a front view of a second embodiment of a perfume bottle according to the invention;

FIG. 11 is an overhead view of a second embodiment of a perfume bottle according to the invention; and,

FIG. 12 is an underside view of a second embodiment of a perfume bottle according to the invention.

The broken line showing of a bottle neck and bottle base in FIGS. 1–12 represent environmental structure and form no part of the claimed design.

The broken lines defining the peripheral boundary of the second embodiment of the claimed design (FIGS. 7–14 12) form no part thereof.
